UNITED STATES PATENT OFFICE

LAWRENCE M. BAYAN, OF EDGEWOOD, RHODE ISLAND

SMOKER'S PACKAGE

Application filed August 16, 1929. Serial No. 386,455.

This invention relates to smokers' articles and has for its main object to provide a handy, novel and artistic container or bowl, filled with tobacco and normally protected by a thin wrapper, the contents of which may be readily and conveniently smoked when desired and the rest then thrown away.

Another object of this invention is to provide an article of the character described resembling a pipe, which may be used and enjoyed like a pipe by inserting a pipe stem in a convenient hole therein.

Still other objects of this invention are to provide an article as characterized hereinbefore which will be artistic in appearance, which will be wrapped or enclosed in a weatherproof cover to retain the tobacco in a desirable condition, which will be handy and convenient to use, inexpensive, and adapted to be distributed in packages containing a plurality of such units ready for use.

Other objects of the invention will be apparent as the specification of the same proceeds.

With these and other objects in view, the invention consists in certain constructions, arrangements and combinations of the parts that I shall hereinafter fully describe and claim.

For a full understanding of the invention, reference is to be had to the following description and accompanying drawing in which,

Fig. 1 is a perspective view indicating a tobacco filled bowl during the operation of wrapping the same in a semi-transparent thin protecting cover.

Fig. 2 is a sectional elevation of a ready tobacco filled bowl with its protecting cover sealed at the bottom thereof.

Fig. 3 is a perspective view of a bowl after the protecting cover has been removed.

Fig. 4 is a sectional elevation of such a bowl indicating the manner in which a stem may be inserted therein prior to being smoked.

Fig. 5 is a perspective view of a bowl of the nature described with a stem inserted therein and ready to be smoked, while

Fig. 6 is a perspective view of a box con-

taining several units of wrapped and sealed tobacco filled bowls, portions of the box being broken away to more clearly show the arrangement of the contents thereof.

Referring now to the drawing by characters of reference, the numeral 10 indicates a container for the tobacco being open at the top and reduced or converging towards a closed bottom of the same, in general resembling a pipe, and having a hole 11 provided therethrough near its bottom.

This container or bowl may be made of any suitable material, like wood, clay, porcelain, cork, or any other fireproof composition, so as to make the same adapted to smoke tobacco therein. The bowl will then be filled with a suitable tobacco 12, in a manner resembling that used in filling a pipe bowl, after which the filled bowl is wrapped or enclosed in a thin weather and waterproof cover 13, which is sealed in any suitable manner, as indicated at 14, so as to hermetically enclose the bowl and the tobacco therein. The protecting and sealing layer may consist of waxed paper or like material and it may be fully or semi-transparent.

In Fig. 1 the protecting layer 13 is shown as brought down to a point 15 and then a piece of cord or a ring 16 is applied therearound to secure the loose ends, whereupon the superfluous material, indicated at 17, may be cut off.

In Fig. 2 the protecting layer 13 is made with overlapped ends 13a and 13b at the bottom of the container, then a seal 18 is applied thereto. In this modification a stem 19 is also indicated which is secured in an appropriate hole 11 in the bowl 10. A registering hole 11a being provided in the sealing wrapper 13 and the material of said wrapper made to closely adhere to the stem 19.

In Fig. 4 is shown a cross section of the bowl 10 with the tobacco therein after the protecting and sealing layer has been removed therefrom. In this normal, and preferred, form of my invention, a separate stem is used which is indicated in an imaginary manner at 19a and which will be inserted in the hole 11 after the wrapper has been re-

moved from the ready container of the tobacco.

Fig. 5 shows a container 10 with the stem 19a inserted in its hole and the whole being 5 ready for smoking.

In Fig. 6 I show a box 20 containing a number of my ready smokers' packages 21 arranged therein and a number of loose stems 22 packed with the same.

10 It is obvious that my invention provides a simple, inexpensive and novel device for the comfort of smokers. The small containers or bowls may be made with many artistic and interesting designs of a cheap material 15 and when their wrappers have been removed they may be smoked by inserting a separate stem or by attaching a stem to the bowl when preparing and packing it. After smoking, the container and stem may be thrown away 20 and a new one taken, if so desired. These ready smokers' packages may also be made with small dimensions adapted to be smoked by ladies and packed and manufactured in an artistic manner, somewhat resembling pack- 25 ages of candy. Said packages may conveniently be served at dinners and other gatherings.

It is also obvious that my invention will obviate the carrying around of a soiled pipe, 30 packages of tobacco, it also will eliminate the operations of filling and cleaning the pipes and will always insure a pipe ready to be smoked, filled with freshly preserved and rightly packed tobacco of the desired quality.

35 What I claim as new, is:

1. A smokers' article, comprising a container of substantially fireproof material, open at the top, having a reduced closed bottom, resembling and adapted to be used as 40 a pipe bowl, and having a hole for a stem near its bottom; a filling of tobacco in said container, and a weatherproof, thin, light sealing cover therearound.

2. A smokers' article, comprising a container of substantially fireproof material, open at the top, having a reduced closed bottom, resembling and adapted to be used as, 45 a pipe bowl, and having a hole for a stem near its bottom; a filling of tobacco in said container, and a weatherproof, thin, light sealing cover therearound, said sealing cover being of transparent material.

3. A smoker's article, comprising a container of substantially fireproof material, open at the top, having a reduced closed bottom, resembling and adapted to be used as a pipe bowl, and having a hole for a stem 50 near its bottom; a filling of tobacco in said container, and a weatherproof, thin, light sealing cover therearound, said sealing cover being an integral piece of flexible material placed on top of said container and wrapped around the same from said top to the bottom 55 thereof, and a member at the bottom of the

container to secure the loose ends of said cover.

4. A smoker's article, comprising a container of substantially fireproof material, open at the top, having a reduced closed bottom, 70 resembling and adapted to be used as a pipe bowl, and having a hole for a stem near its bottom; a filling of tobacco in said container, and a weatherproof, thin, light sealing cover therearound, said sealing cover being an integral piece of flexible material placed on top of said container and wrapped around the same from said top to the bottom thereof, and a member at the bottom of the 75 container to secure the loose ends of said cover, said sealing cover being transparent.

5. A smoker's article, comprising a container of substantially fireproof material, open at the top, having a reduced closed bottom, 80 resembling and adapted to be used as a pipe bowl, and having a hole for a stem near its bottom; a filling of tobacco in said container, and a weatherproof, thin, light sealing cover therearound, said sealing cover being an integral piece of flexible material placed on top of said container and wrapped around the same from said top to the bottom 85 thereof, and a member at the bottom of the container to secure the loose ends of said cover, said sealing cover being transparent. 90

Signed at Providence, in the county of 100 Providence, and State of Rhode Island, this 10th day of August, 1929.

LAWRENCE M. BAYAN.
